Primary Examiner — Marianne Pandozzi*Assistant Examiner* — Jae Liang(74) *Attorney, Agent, or Firm* — Hodgson Russ LLP(57) **CLAIM**

The ornamental design for a beverageware, as shown and described.

DESCRIPTION

FIG. 1 is a front perspective view of a first embodiment of a beverageware in used with an exemplary lid showing my new design;

FIG. 2 is a front view thereof with the lid removed for ease of illustration; the rear view being a mirror image thereof;

FIG. 3 is a right side view thereof; the left side view being a mirror image thereof;

FIG. 4 is a top view thereof;

FIG. 5 is a bottom view thereof; and,

FIG. 6 is a front view of a second embodiment of a beverageware; rear and side views are being mirror images thereof. The broken line shown in the figure drawings are included for the purpose of illustration and form no part of the claimed design. The stippled area in FIG. 6 indicates a matte surface in contrast to the remainder of the beverageware.
